UNITED STATES PATENT OFFICE.

JESSE FULENWIDER, HARRY FULENWIDER, EDWARD W. ROBINSON, AND HARRY NORRIS, OF SAVANNAH, GEORGIA, ASSIGNEES TO HARRY FULENWIDER AND JESSE FULENWIDER, OF SAVANNAH, GEORGIA.

LOCK-ROOFING-FORMING MACHINE.

Application filed June 26, 1926. Serial No. 118,721.

The object of this invention is to provide a machine for producing folds in the edges of a roofing sheet permitting of engagement with adjacent sheets, and to effect this result by the use of a stationary bar having a V-shaped channel in one edge thereof, and to provide in connection with the bar specified, a movable complementary bar also having a V-shaped channel in one edge, the walls of the respective channels converging, and the edge portion of one bar being adapted to enter the channel portion of the oppositely located bar,—means also being provided for advancing the movable bar towards the stationary bar.

A further object is to provide means for adjusting the position of the movable bar, and further to provide means for throwing out a clutch when the forming bars are separated.

With the foregoing and other objects in view, the invention consists in the novel construction and arrangement of elements described, illustrated and claimed, it being understood that modifications may be made within the scope of the claims, without departing from the spirit of the invention.

In the drawings forming part of this application,

Figure 1 is a view of the machine in top plan.

Figure 2 is a view in elevation.

Figure 3 is a view of the sheet in edge elevation, showing the fold or folds produced by the forming bars.

Figure 4 is a further view in edge elevation, showing the folded portions after they have been placed under pressure.

Figure 5 is a detail view in perspective showing means for throwing out the clutch when the bars are separated.

The machine includes a frame 10 mounted upon inverted channel elements 11 and 12, and mounting in bearings 13 a horizontal shaft 14. Also mounted on said frame 10 are frames of the form shown at the right in Figure 2, and shown in top plan in Figure 1, these frames each including a leg member 15, an upper bend 16 and a downwardly extending inclined portion 17, over which the metallic sheets are to be fed. The portion 17 merges into a brace 18 having an offset end portion 19 secured by a bolt 20 to leg 15.

Mounted by suitable means on the main frame is a stationary bar 23 provided with a channel portion 24, the walls of which converge inwardly, and opposite this bar 23 is a movable bar 25 having a channel 26 formed in the edge thereof, this channel also having converging walls, and the upper walls of each channel being reversely inclined, and likewise the walls of the lower portions of the respective channels. The bars 23 and 25, constituting forming devices, are not in the same plane, but the edge portion 23' of bar 23 is opposite the central portion of the channel 26 in bar 25, so that when the bar last named is advanced against the sheet of material to be formed, a double fold of the form illustrated in Figure 3, or substantially that form, will be produced.

In Figures 3 and 4, the folds are designated 28 and 29, and in Figure 4, it is to be assumed that pressure has been applied in any suitable manner, to bring the folds into closer relation than shown in Figure 3. A corrugation 30 in the sheet may be produced, either before or after the folds 28 and 29, are formed.

Connected with forming bar 25, or rather mounting that bar, is a bar 32 including a cutaway portion 33, in which the forming bar 25 is directly mounted. Connected with bar 32 are yokes or the like 34, which have pivotal connection with rods 36 adjustably mounted in elements 37 and retained in an adjusted position by lock nuts 38. These elements 37 are connected at 39 with eccentric straps 40, the straps passing around eccentric members 41. The elements 41 are mounted on shaft 14, and the rotation of the shaft provides for the movement of the bar 25 thru the connections specified.

A collar 44 is splined on shaft 14, and constitutes a clutch element cooperating with clutch element 45 on the hub of a gear wheel 46 meshing with pinion 47 on shaft 48. This shaft last named carries pulley wheels 49 and 50, thru either of which drive is imparted to shaft 14.

In order to throw out the clutch at the proper time, that is, when the bars 25 and 23 are separated, collar 44 is provided with an extension or lug 52, this device serving the purpose of a finger and being engaged by the end of head 53 formed with a bevelled portion or cam surface 54. Head 53 is car-

ried by stem 55, and the latter is moved upwardly for the purpose of throwing head 53 into operative position so that the clutch may be thrown out when finger 52 is in the 5 position of Figure 5, at which time the bar 25 will be separated from bar 23. A spring 56 encircles shaft 14 between the bearing 13 and collar 44, and controls in part a movement of said collar.

10 The stem 55 is controlled by an arm 58 pivoted at 59 and having connection by link 60 with foot operated lever 61, the outer end of which is normally retained in an upper position by spring 62, it being understood 15 that pressure upon the pedal 63 depresses the outer end of lever 61 for controlling the position of head 53 with reference to the engagement thereof with finger 52.

Having thus described the invention, what 20 is claimed is:

1. In a machine of the class described, a stationary forming plate having a longitudinal channel therein, a movable forming plate having a channel therein, the channels 25 opening towards each other, and the edge wall of one channel being positioned to enter the central portion of the other channel, means for advancing the movable channel plate towards the stationary channel plate 30 and means for supporting the work in an inclined plane extending upwardly from the plane of the stationary forming plate.

2. In a machine of the class described, a stationary forming plate having a longitudinal channel therein, a movable forming plate having a channel therein, the channels 35 opening towards each other, and the edge wall of one channel being positioned to enter the central portion of the other channel, means for supporting the work in an inclined plane 40 extending upwardly from the plane of the stationary forming plate, and means including an automatically and mechani-

cally controlled clutch element, for advancing the movable plate to position for bending a metallic sheet between this element and the stationary plate. 45

3. In a machine of the class described, a stationary forming plate and a movable forming plate, these plates having channels 50 in the approaching edge portions thereof, the channels being slightly out of horizontal alignment, means for advancing and retracting the movable plate with reference to the other plate, and adjustable means for determining the extent of movement, said advancing means including eccentric mechanism, a shaft mounting one element of each eccentric, a clutch collar splined on the shaft, a clutch collar cooperating with the 55 collar first named, driving means with which the cooperating collar is rigidly connected, a finger carried by the splined collar, and means adapted to be thrown into the path of the splined collar for moving it out of 60 engagement with the other collar.

4. In a machine of the class described, a stationary forming plate having a longitudinal channel therein, a movable forming plate having a channel therein, the channels 70 opening towards each other, and the edge wall of one channel being positioned to enter the central portion of the other channel, and means for advancing the movable channel plate towards the stationary channel plate, 75 said plate advancing means including clutch elements and pedal controlled means longitudinally movable, for engaging one of the clutch elements and moving said element out of engagement with the other. 80

In testimony whereof we affix our signatures.
